United States Patent Office.

BENJAMIN F. HORN, OF BOSTON, MASSACHUSETTS.

Letters Patent No. 92,449, dated July 13, 1869.

ASH-SIFTER.

The Schedule referred to in these Letters Patent and making part of the same.

To all persons to whom these presents may come:

Be it known that I, BENJAMIN F. HORN, of Boston, in the county of Suffolk, and State of Massachusetts, have invented a new and useful Improvement in Coal or Ash-Sifters; and I do hereby declare the same to be fully described in the following specification, and represented in the accompanying drawings, of which—

Figure 1 denotes an under-side view of the sifter-drum, and its cap or cover, the same showing the door of the drum, and the appliances by which it is held in place, with respect to the mouth of the drum, while the said drum may be in revolution.

Figure 2 is a longitudinal section, and

Figure 3, a transverse section of the sifter.

The cap or cover of the sifting-drum consists of a square box, A, and a circular base or flange, B, the said box being elevated on the circular base, and made to open through it.

The circumference of the base, I usually surround with a metallic band or hoop, a.

When in use, the cap or cover rests directly over the rotary sifting-drum C, and its shaft D.

The sifting-drum is composed of two circular heads, b b, and a peripheral rim or jacket, c, of woven wire, there being an open space or mouth, d, between the ends of the rim.

There is, to such space, a door, E, made of a sheet, e, of woven wire, and a frame, f, to embrace and support the edges of the sheet.

This door rests on the circumferences of the two heads, and, at one end, extends underneath two hooked lugs, g g, projecting from the head.

When in place over its opening, or the mouth of the drum, the door also rests against a stud, h, which extends from the other head, and serves, with two turn-buttons, i i, applied to the head, near the opposite corners of the door, and so as to button over the door, to hold the door to the drum.

A shaft, D, provided with a crank, G, extends axially through the drum, and the notches of two guides or projections, k k, extend down from the cover. These guides merely support the shaft in the middle of the cover, or keep it therein.

Near its crank, the shaft is provided with one or more grooves, l l, extending transversely around it. At or near its opposite end, it terminates in a long journal, m, furnished with a shouldered head, n. The shoulder of the head, by resting against the periphery of the flange of the cover, serves to keep the shaft in its due relation with the cover.

The cover and the drum, with the shaft, made as described, are intended for use either over a box or a barrel.

As barrels vary more or less in diameter, the shaft, by means of the transverse groove and the long journal, can be adapted to any barrel, the groove receiving the upper extremity of one of the staves of the open end of the barrel, when the shaft is placed diametrically across the barrel, in which case the long journal will rest on the upper end of the opposite stave. The cover, having a circular base, will close the barrel, so as to prevent the escape of ashes therefrom while the drum may be in revolution, such drum being revolved by manual power applied to the crank.

I make no claim to a cylindrical drum as a sifter, nor the combination of such with a case, to surround the drum more or less; nor do I claim the combination of such drum and case with a vessel or box to receive the siftings, or matters which may be discharged by the drum.

What I claim as of my invention, is as follows:

I claim the drum-shaft, as made, with the transverse groove, (arranged near one end of the drum,) and with the long journal and head to extend beyond the other end of such drum, as set forth, the same being as specified.

I also claim the combination and arrangement of devices for holding the mouth-piece or door of the sifting-drum in place on the mouth of the drum, such devices consisting of the two hooked lugs, the stud, and the two turn-buttons, the whole being to operate as specified.

B. F. HORN.
